(57) CLAIM

The ornamental design for a combined stamp pad and lid, as shown and described.

DESCRIPTION

FIG. 1 is a top perspective view of a combined stamp pad and lid showing my new design;

FIG. 2 is a bottom perspective view thereof;

FIG. 3 is a rear perspective view thereof;

FIG. 4 is a side elevation thereof;

FIG. 5 is a front perspective view thereof;

FIG. 6 is a top perspective view of the design shown in FIGS. 1 through 5 with the lid removed;

FIG. 7 is a side elevation thereof;

FIG. 8 is a front perspective thereof;

FIG. 9 is a rear perspective view thereof;

FIG. 10 is a top plan view of the lid member of the design shown in FIGS. 1 through 5;

FIG. 11 is a bottom plan view thereof;

FIG. 12 is a side elevation thereof;

FIG. 13 is a rear elevation thereof; and,

FIG. 14 is a front elevation thereof shown in an inverted condition.
